ABSTRACT

Index card, file or similar flat element for a filing system, which element along one edge is provided with a code which can be read in a direction parallel to the main plane of the element. For this purpose the element is provided along one edge with a reflector of transparent material comprising at the position of the code a surface which makes an acute angle with the main plane of the element, in which surface the code is reflected.

**INDEX CARD, FILE OR SIMILAR FLAT ELEMENT
FOR A FILING SYSTEM**

The invention relates to an index card, file or similar flat element for a filing system, in which a number of such elements are filed away vertically side by side, the element being provided with means to read out a code identifying the element in a direction parallel to a main plane of the element.

Filing systems are known, e.g. for X-ray photographs in hospitals, in which special files can automatically be extracted from a plurality of files. For this purpose the files are placed vertically side by side on shelves or they are suspended in racks, and one edge, e.g., the top edge, is provided with a bar in which a coding strip with a sufficiently large transverse dimension, provided with a black and white block code can be placed. An photo-electric reading device can be moved mechanically along the shelves to sense all the code strips and to extract those files the code of which satisfies a pre-selected searching program.

The coding and fastening of such code strips is troublesome, particularly if the files have small dimensions and if transverse dimension of the code strips is as small as possible to reduce the required space. Furthermore it is possible that the code strips may be fastened to the wrong files because of the fact that the files and code strips do not form a unity.

It is a principal object of the present invention to provide a file element, in which the code and the element (index card, document file etc.) form an inseparable unit, and in which the code can easily be applied, while the transverse dimension of the required space per element is as small as possible.

In one embodiment of the invention the code is placed adjacent one edge of the element and in the main plane of the element, the element being provided with a reflector extending parallel to said edge at the position of the code, said reflector having a surface making an acute angle with the main plane of the element, in which surface said code is reflected.

In another embodiment the reflector by way of example is a prism of a transparent material, placed with one side on the code, a slanting side reflecting the code. To assure that the light is converged onto the photoelectric elements of the reading device, the surface of the prism which is turned to the sensing direction may have a cylinder form.

Instead of direct attaching the reflector to the card or the cover of the file element in a preferred embodiment of the invention the reflector is part of an envelope which at least at the position of the reflector is transparent and in which the material to be filed bearing a code can be placed. An envelope of this kind assures an exact positioning of the reflector, is easy to handle and is reusable.

Other and further objects and advantages of the invention will become apparent from a reading of the following specification taken in conjunction with the drawing, in which:

FIG. 1 shows perspectively a preferred embodiment of the file element according to the invention,

FIG. 2 shows a side elevation of a part of a filing system with two files according to the invention, and

FIG. 3 shows a partial cross-section of the element as showed in FIG. 1.

In FIG. 1 is shown a transparent envelope 1, e.g., made of plastic foil, which is open at the top. In said

first envelope fits a second envelope 2 of non-transparent material on which the data to be filed can be written and in which a number of papers, photographs 3 etc. can be stored. One of the edges of the envelope 2 bears a code, consisting of a black and white block code pattern 4, by means of which the file can be identified. In the inserted position of envelope 2 the code is located under a prismatic bar 5 of transparent material, e.g. plastic that is fastened to the envelope 1, e.g., by means of glue. The slanting side 6 of this prism (FIG. 3) reflects the code in such a way that said code can be read in a direction in the plane of the element, either visually or by means of a photo-electric reading device which can be moved along the front edges of a number of elements positioned vertically side by side. The light emerging from the prism can be formed into a beam by curving the surface 7 of the prism in the form of a cylinder.

The code 4 is applied to the file element 2 together with the further data so that they cannot be separated. The code may for instance be applied either by means of a graphic pencil or by means of a key board controlled code printer.

The height of the prism 5 can be small and is determined mainly by the characteristics of the reading head used. FIG. 2 further shows a solution giving a saving of space which can be used in case of a small amount of data to encode. On the envelopes 8 and 8' in FIG. 2 the code covers slightly less than half the height of the envelope. As a result the prisms 9 and 9' also extend over half the height. Furthermore they are applied in an alternating way, that is prism 9 in the upper half and on one side of the element, prism 9' in the lower half and on the other side. This permits the positioning of the envelope between parts of the frame 10 and 11 of the filing system so that the prisms are in a direct line. By this arrangement one has to use two kinds of envelopes. The advantage however is that two times more files can be stored in the same space.

While disclosures of preferred embodiments have been provided, it will be apparent that numerous modifications and variations thereof may be made without departing from the underlying principles of the invention. So the invention is by no means delimited to the form of the envelope as described; moreover the reflector 5 may be fastened directly to the file element.

It is also possible that use is made of reflectors of another type, e.g., slanting reflecting metal strips, which are fastened to the envelope by means of a turned back end portion.

What I claim is:

1. A filing system comprising a plurality of generally rectangular planar outer envelope members, means for supporting said envelope members in parallel, side-by-side relation with an edge portion of each of said envelopes exposed for visual access from a direction parallel to the plane of said envelopes, said envelopes having an information bearing substrate disposed therein, coded indicia formed adjacent one edge of said substrates, transparent window portions formed in said envelopes adjacent said exposed edge portions, said window portions being coextensive with and in registry with said coded indicia of said substrates so that said indicia are exposed through said window portions, each said envelope including a prism member on the outer surface thereof, said prism members being disposed in covering relation of said window portions and in registry with said indicia on said substrate, said prism members including a reflector wall angularly oriented with respect to said envelope and directed toward said edge of said envelope, whereby said indicia on said substrate are visible through said prism members when viewed from said direction.
